DESIGN FOR A DRINKING CUP

Elmer J. Stumpf, Los Angeles, Calif., assignor to New Plastic, Los Angeles, Calif., a corporation of California

Application January 15, 1945, Serial No. 117,428

Term of patent 14 years

(Cl. D44—9)

To all whom it may concern:

Be it known that I, Elmer J. Stumpf, a citizen of the United States, residing in the city of Los Angeles, county of Los Angeles, State of California, have invented a new, original, and ornamental Design for a Drinking Cup, of which the following is a specification, reference being had to the accompanying drawing, forming a part thereof.

I claim:

The ornamental design for a drinking cup, as shown.

E. J. STUMPF.
